MAIL BOX

Gregory O. Corkery, St. Louis, Mo., assignor to Jackes-Evans Manufacturing Company, St. Louis, Mo., a corporation of Delaware

Filed July 17, 1968, Ser. No. 12,801

Term of patent 14 years

Int. Cl. D31

U.S. Cl. D74—9

FIGURE 1 is a front elevational view of my new design for a mail box illustrating the contrasting wood applique on the hinged lid;

FIGURE 2 is a rear elevational view thereof;

FIGURE 3 is a side elevational view, the opposite side presenting a mirror image;

FIGURE 4 is a bottom plan view thereof; and

FIGURE 5 is a top plan view thereof.

The essential features of my design reside in the portions shown in solid lines, a conventional ornament and a part thereof being shown in broken lines in FIGURES 1 and 5, respectively.

I claim:

The ornamental design for a mail box, substantially as shown and described.
